FIG. 1 is a perspective view of a light emitting diode showing my new design;

FIG. 2 is a plan view of the light emitting diode having four LED chips according to the embodiment of FIG. 1;

FIG. 3 is a left view of the light emitting diode according to the embodiment of FIG. 1;

FIG. 4 is a front elevational view of the light emitting diode according to the embodiment of FIG. 1;

FIG. 5 is a right view of the light emitting diode according to the embodiment of FIG. 1;

FIG. 6 is a bottom plan view of the light emitting diode according to the embodiment of FIG. 1; and,

FIG. 7 is a rear view of the light emitting diode according to the embodiment of FIG. 1.
